UNITED STATES PATENT OFFICE.

RAYMOND B. GILCHRIST, OF NEWARK, NEW JERSEY, ASSIGNOR TO THE GILCHRIST COMPANY, OF NEWARK, NEW JERSEY, A CORPORATION OF NEW JERSEY.

DRINK MIXER.

Application filed March 17, 1922. Serial No. 544,399.

To all whom it may concern:

Be it known that I, RAYMOND B. GILCHRIST, a citizen of the United States, and a resident of Newark, in the county of Essex and State of New Jersey, have invented certain new and useful Improvements in Drink Mixers, of which the following is a full, clear, and exact description.

The invention relates to drink mixers.

In machines for this purpose, the liquid constituents of the drink to be mixed are usually poured into a receptacle which is generally designated a "shaker," from many different containers disposed away from the mixer. The receptacle with these constituents therein is brought to the mixer and placed in operative relation thereto and is removed from the machine after each mixing operation to discharge its contents. This is rendered necessary, because so many different ingredients and flavors are used in making drinks that they are, in nearly all cases, mixed individually. It is usually necessary to run the agitator for a considerable period to properly blend or mix the constituents and, therefore, it is desirable that provision be made for retaining the receptacle and agitator in operative relation to permit the dispenser to perform other duties during the mixing operation. In drink mixing, it thus becomes necessary to frequently place the receptacle, containing the constituents, into cooperative relation to the agitator and to withdraw it from the machine to discharge its contents and cleanse the receptacle between mixing operations.

A desideratum in this art is to expedite and simplify the operations necessary to bring the receptacle and agitator into cooperative relation, to maintain them in such relation, in starting and stopping of the motor and the removal of the receptacle. Heretofore, in machines whereof I am aware (excepting those exhibited in concurrently pending applications), it has been necessary in their use to manually manipulate the receptacle into operative position and withdraw it therefrom and to additionally perform some separate step or operation, such as lowering the motor and agitator together, or shifting the agitator and its shaft into the receptacle and relatively to the motor, or raising and locking a receptacle support to establish and maintain cooperative relation of the receptacle and agi-

tator or to control the operation of the machine. Another desideratum in this art is to simplify the machine by dispensing with movable connections in and for the mechanism for driving the agitator.

In practice, it has been found that when the agitator is eccentrically disposed in the receptacle while it is in operation, the mixing of the drink will be accelerated, because when the agitator is concentrically disposed in the receptacle, there is a greater tendency toward the formation of a vortex and the rotation of the liquid with the agitator. It has also been found desirable to make provision for the withdrawal of the agitator from the liquid before the receptacle passes below the agitator, so that it will cleanse itself by centrifugal force and discharge the adhering material into the receptacle. By producing a vortex while the receptacle is being withdrawn, the exit of the agitator from the mixed liquid is facilitated, so that the cleansing operation will occur before the receptacle is completely withdrawn.

One object of the present invention is to provide an improved drink mixer in which these additional operations or steps are dispensed with and in which provision is made for shifting the agitator to cause it to operate eccentrically while the receptacle is locked in operative position and thus accelerate the agitation of the liquid and to cause it to operate concentrically in the receptacle while the receptacle is being withdrawn from and shifted into operative position.

Another object of the invention is to provide a receptacle controlled machine which is equipped so that the receptacle will be manually manipulated into and out of its operative position and in which the motor is shifted to shift the agitator relatively to the receptacle, as a result of said manual shift.

Other objects of the invention will more fully appear from the following description.

The invention consists in the several novel features hereinafter set forth and more particularly defined by claims at the conclusion hereof.

In the drawings: Fig. 1 is a vertical section of a machine embodying the invention, parts being shown in elevation, the receptacle carrier being in its lowered position.

Fig. 2 is a horizontal section on line 2—2 of Fig. 1. Fig. 3 is a vertical section, the receptacle carrier being shown in position to hold the receptacle in operative position. Fig. 4 is a perspective of the receptacle carrier.

The invention is exemplified in a machine comprising a base 10, usually adapted to rest on a counter or table, a supporting standard 9 secured to said base by bolts 8 and an electric motor 7 which is pivotally sustained and connected by screws 13 in arms 9^a formed on the upper end of standard 9. An agitator shaft 11, projected downwardly from and secured to the rotor of the motor 7, is provided at its lower end with an agitator 12 of suitable construction, as well understood in the art. Shaft 11 has fixed relation to the rotor of the motor 8, thus avoiding a sliding connection for permitting the agitator to be raised and lowered into the receptacle 19 which contains the material to be mixed. There is sufficient clearance below and around the agitator to permit the receptacle to be placed into operative position from below without moving the agitator. A case 15, containing a snap-switch of usual construction with members connected to control the motor 7, is fixedly secured to the case of the motor 7 with a button 16 which is adapted to open the switch when it is pushed upwardly into case 15 and to close the switch when it is pulled downwardly, as well understood in the art. The switch-members in case 15 may be of standard construction, so that no detailed illustration has been deemed necessary. Yielding contact-strips 18^a, adapted to enter a switch socket of usual construction, project rearwardly from said case, so that the necessary electrical connections to supply current to the motor will be made by pushing an ordinary conductor socket which is adapted to receive said contact strips and is connected by a flexible cord to a suitable source of energy, into connected relation with said strips.

The mechanism for guiding the receptacle 19 into and holding it in operative relation to the agitator and guiding it during its withdrawal, comprises a support or shelf 22 upon which the bottom of the receptacle 19 is adapted to rest; a standard 21, to which support 22 is secured; and a hook or abutment 20 adapted to extend over the rim of the receptacle and engage the inner periphery of the upper portion thereof to secure the receptacle against lateral movement. The hook 20, support 22 and upright 21 constitute a carrier for holding the receptacle while it is in operative position and which is operable upwardly and downwardly by manual shift of the receptacle. Screws 45 extend through elongated slots 46 in upright 21 and are adapted to secure

hook 20 in different positions to adapt the carrier to securely hold vessels of different heights. An upper arm 23 and a lower arm 24 rigid with the carrier-standard 21 extend rearwardly through a slot 26 in front of standard 9 and are notched, as at 27, to fit around the sides of said slot and slidably guide the upper and lower portions of the carrier. Lugs 30, projecting laterally from the upper arm 23 and rigid thereon, are adapted to engage notches 31 in the rear faces of the walls forming the sides of the slot 26 to lock the carrier and the receptacle in operative relation to the agitator.

A lever 35 has its upper end rigidly secured to the casing of the motor 7 and is provided with an elongated vertically extending slot 36 in which operates a stud or roller 37 which is carried at the rear end of the upper carrier arm 23. This connection between the carrier and the motor is adapted to rock the motor to shift the agitator into different lateral positions while the receptacle is in manual transit to and from its operative position. The pivotal connection exemplified by screws 13 between the motor and the standard 9 is disposed forwardly of the center of the motor so that it will be hung with a tendency to swing the agitator shaft 12 and lever-arm 35 forwardly. This will cause the weight of the motor to be applied through lever-arm 35 to press the receptacle carrier forwardly and cause it to be automatically locked in its raised position. The forward pressure upon the carrier will cause lugs 30 to be forced into notches 31 when the carrier reaches its operative position. The carrier is slidable vertically while the lever arm 35 is fulcrumed at 35^a. As the carrier is moved forwardly or backwardly in locking and unlocking the carrier, the connection between stud 37 and slot 36 will cause the lever-arm and motor to be swung about said fulcrum and correspondingly shift the agitator 12 laterally.

A lever 40 is pivoted to lever-arm 35 at 35^a and has its upper end 42 connected to push the switch-button 16 upwardly and downwardly when the lever is shifted relatively to the lever arm 35. Stud 37 on the carrier also operates in a slot 43 which is provided with a cam-portion 44 to cause the switch-lever to be shifted relatively to the lever-arm 35 to close the switch during the upward movement of the carrier and receptacle and to open the switch to stop the motor during the lowering of the receptacle.

The operation of the machine will be as follows: Normally, the carrier will be in its lowered position shown in Fig. 1. The operator, grasping the receptacle, will place it under hook 20 so that the upper margin of the receptacle will be locked to the carrier and will swing its lower portion backwardly towards the standard 21 to bring

the bottom of the receptacle on or over support 22 it being understood that the hook is formed with sufficient clearance to permit the angular insertion of the receptacle into 5 the hook. This will cause the receptacle to be locked to the carrier so that the latter will be operable upwardly and downwardly by the receptacle. The operator will manually raise the receptacle until it reaches its 10 operative position around the agitator 12. In transit to said position, stud 37, acting upon cam-portion 44 of slot 43, will shift the switch-lever 40 relatively to the arm 35 and cause it to pull the switch-button 16 15 downwardly to close the switch and start the motor 7. As the receptacle reaches its operative position around the agitator, lugs 30 will reach notches 31. Off-center weight of motor 7, acting through lever-arm 35, will 20 press stud 37 forwardly, causing lugs 30 to pass into notches 31 and thus lock the carrier and receptacle in their operative position. In effecting forward movement of the 25 upper end of the carrier to lock it, stud 37 will swing lever-arm 35 and the motor about its fulcrum 13 and cause the agitator to be positioned eccentrically in the receptacle. In such position, the agitator will operate effectively in the contents of the receptacle. 30 When the mixing operation has been completed, the operator will grasp the receptacle and push its upper end rearwardly against the off-center weight of the motor and lever-arm 35 to withdraw lugs 30 from notches 31 35 and release the carrier and receptacle so they can be lowered. This backward movement of the upper portion of the carrier will cause stud 37 to swing motor 7, so that the agitator 12 will be disposed in substantially concentric position in the receptacle during its withdrawal. By shifting the agitator to 40 this concentric position, a vortex will be produced while it is still rotating. As a result, the withdrawal of the agitator from 45 the liquid will be expedited and it will centrifugally cleanse itself while the receptacle is still in position to catch the material thrown off by the agitator. During the 50 manual lowering of the receptacle, stud 37 will shift the lower end of switch-lever 40 forwardly about its pivot 41 on lever-arm 45 and cause its upper end 42 to push the switch-button 16 upwardly and open the switch to stop the motor. 55 The invention exemplifies a drink mixer in which the motor carrying the agitator is shiftable by the receptacle; in which a receptacle is locked in and operates a carrier which shifts the motor and agitator; in 60 which the agitator is shifted transversely to operate eccentrically in the receptacle during the mixing operation and more nearly concentrically during placement or removal of the receptacle into its operative position; 65 in which the motor is suspended in off-center

relation to automatically retain the locking means for the receptacle-carrier in operative relation; and which is simple in construction.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a machine of the character described, the combination of a support, a motor movably connected to the support, an agitator 80 driven by the motor, and means for automatically shifting the motor operable by manual manipulation of the receptacle itself into its operative position.

2. In a machine of the character described, 85 the combination of a support, a motor movably connected to the support, an agitator driven by the motor and supported from above with sufficient clearance to permit a receptacle with an open top to be placed into operative position around the agitator while the latter is in its operative position, and means for automatically shifting the motor by manual manipulation of the receptacle 90 itself into and out of its operative position.

3. In a machine of the character described, the combination of a support, a motor movably connected to the support, an agitator 100 driven by and movable with the motor, and means for automatically shifting the motor to laterally shift the agitator, operable by placement of the receptacle in and its removal from its operative position.

4. In a machine of the character described, 105 the combination of a support, a motor pivotally connected to the support, an agitator driven by and supported from the motor, and means for automatically shifting the motor and agitator by manual manipulation of the receptacle itself into and out of its operative position around the agitator.

5. In a machine of the character described, the combination of a support, a motor pivotally connected to the support, an agitator 115 driven by and movable with the motor and supported from above with sufficient clearance to permit a receptacle with an open top to be placed into operative position around the agitator while the latter is in its operative position, and means for automatically shifting the motor and agitator by manual manipulation of the receptacle itself into 120 and out of its operative position.

6. In a machine of the character described, the combination of a support, a motor pivotally connected to the support, an agitator driven by and secured to rotate directly with the rotor of the motor and movable laterally 125 when the motor is shifted, and means for 130

automatically shifting the motor and agitator by manual manipulation of a receptacle itself into and out of its operative position.

5 7. In a machine of the character described, the combination of a support, a motor carried by the support, an agitator driven by the motor, means to hold the receptacle so the agitator will be eccentrically disposed 10 therein while the receptacle is in its operative position, and means for shifting the agitator transversely in the receptacle to operate centrally therein.

8. In a machine of the character described 15 the combination of a support, a motor carried by the support, an agitator driven by the motor, means to hold the receptacle so the agitator will be eccentrically disposed therein while the receptacle is in its operative position, and means for automatically 20 shifting the agitator transversely in the receptacle to operate centrally therein at other times.

9. In a machine of the character described 25 the combination of a support, a motor movably connected to the support, an agitator driven by and movable with the motor and supported from above with sufficient clearance to permit a receptacle with an open top 30 to be placed into operative position around the agitator while the latter is in its operative position, means to hold the receptacle so the agitator will be eccentrically disposed 35 therein while the receptacle is in its operative position, and means for automatically shifting the agitator transversely in the receptacle to operate centrally therein at other times.

10. In a machine of the character described, 40 the combination of a support, a motor movably mounted on the support, an agitator driven by the motor, a receptacle-carrier movably connected to the support provided with means whereby it may be shifted by the 45 manual manipulation of the receptacle itself, and means operable by the carrier for shifting the motor.

11. In a machine of the character described, 50 the combination of a support, a motor movably mounted on the support, an agitator driven by the motor and supported from above with sufficient clearance to permit a receptacle with an open top to be placed into operative position around the agitator while the latter is in its operative 55 position, a receptacle-carrier movably connected to the support for and operable by manual manipulation of the receptacle itself, and means operable by the carrier for 60 shifting the motor and agitator.

12. In a machine of the character described, 65 the combination of a support, a motor pivotally connected to the support, an agitator driven by and movable with the 70 motor and supported from above with suf-

ficient clearance to permit a receptacle with an open top to be placed into operative position around the agitator while the latter is in its operative position, a receptacle-carrier movably connected to the support for 70 and operable by manual manipulation of the receptacle itself, and means operable by the carrier for shifting the motor and agitator.

13. In a machine of the character described, 75 the combination of a support, a motor, an arm pivotally connected to the support and to which the motor is secured, an agitator driven by and supported from the motor on the motor-casing, and means for automatically shifting said arm to shift the 80 motor, said means being shiftable by manual placement or removal of a receptacle itself.

14. In a machine of the character described, 85 the combination of a support, a motor pivotally connected in off-center relation to the support, an agitator driven by and supported from the motor, and means for automatically shifting said motor, said means being shiftable by manual placement 90 or removal of a receptacle itself.

15. In a machine of the character described, 95 the combination of a support, a motor movably connected to the support, an agitator driven by and supported from the motor, means for automatically locking a receptacle in operative position around the agitator, and means for shifting the motor and agitator operable by manual manipulation of the receptacle itself into and out of 100 its operative position.

16. In a machine of the character described, 105 the combination of a support, a motor movably connected to the support, an agitator driven by and supported from the motor, means for controlling the operation 110 of the motor, and means for automatically shifting the motor by manual manipulation of a receptacle itself into its operative position and around the agitator and for controlling the switch.

17. In a machine of the character described, 115 the combination of a support, a motor movably connected to the support, an agitator driven and supported from the motor, with sufficient clearance to permit a receptacle with an open top to be placed into operative position around the agitator while the latter is in its operative position, means for controlling the operation of the motor, 120 and means for automatically shifting the motor by placement of a receptacle into and out of operative position and around the agitator and for controlling the switch.

18. In a machine of the character described, 125 the combination of a support, a motor pivotally connected to the support, an agitator driven by and supported from the motor, an arm secured to the motor, a switch 130 for controlling the motor and means for auto-

matically shifting the arm to swing the motor.

19. In a machine of the character described, the combination of a support, a motor movably connected to the support, an agitator driven by and supported from the motor, an arm secured to the motor, a switch for controlling the motor, means for automatically shifting the arm to swing the motor, and a lever for operating the switch 10 mounted on said arm.

Signed at Newark, N. J., this 11th day of February, 1922.

RAYMOND B. GILCHRIST.
